UNITED STATES PATENT OFFICE.

HANS LUNDQUIST, OF CHICAGO, ILLINOIS, ASSIGNOR TO UNITED STATES SPECIALTY CORPORATION, OF CHICAGO, ILLINOIS, A CORPORATION OF ILLINOIS.

THREADING MACHINE.

Application filed December 6, 1919. Serial No. 342,987.

To all whom it may concern:

Be it known that I, HANS LUNDQUIST, a citizen of the United States, residing at Chicago, in the county of Cook and the State 5 of Illinois, have invented new and useful Improvements in Threading Machines, of which the following is a specification.

This invention relates to improvements in machines for threading ribbons through 10 laces, or the like.

It is an object of the invention to provide a machine whereby ribbons may be inserted through the mesh of lace so that the ribbon alternately is placed above and below different strands of the lace.

It is also an object of the invention to provide a device for automatically gathering portions of lace fabrics, and to insert the ribbon into the mesh of the lace by 20 straightening out or stretching the gathered portion of the lace.

An object of the invention is also to provide a machine in which the arrangement of the lace, with respect to the ribbon support, is effected automatically by a threading needle, through relative movement of the threading needle and lace.

It is, furthermore, an object of the invention to provide in a machine of this 30 character means, which in this instance—by way of example—are movably supported by a threading needle, for successively and alternately deflecting strands of the lace work so as to place them above and below the 35 threading needle respectively.

An object of the invention is also to support a threading needle pivotally at either one of two selectively determined points, whereby either a portion of the needle may 40 be rendered free to permit the removal of the lace gathered thereon, or a selectively determined length of lace may be gathered or ruffled through advancement of the lace in direction towards the pivotal supporting 45 point.

With these and numerous other objects in view, an embodiment of the invention is described in the following specification, and is illustrated in the accompanying drawings, 50 the novel features being pointed out in the appended claims.

In the drawings—

Fig. 1 is a perspective view of the complete machine;

Fig. 2 is a vertical longitudinal section

through the same, certain parts being shown in elevation;

Fig. 3 is another vertical section through a portion of the machine on line 3—3 of Fig. 2;

Fig. 4 is a horizontal section and partly top plan view of the needle support;

Fig. 5 illustrates the needle in top plan view in two positions;

Fig. 6 is partly detail section and partly 65 elevation through the yielding support for a feed roller, and

Figs. 7, 8, 9, and 10 are diagrammatic illustrations of the movably supported head of the threading needle in different positions.

The machine comprises a substantially rectangular support 1, in the form of a casing, which is closed at its sides, end walls, and top, but which may be open at its bottom. The interior of the casing may serve to receive a driving element, as, for instance, an electric motor 2, which is suitably supported by straps 3 in this casing. The armature shaft of the motor carries in the illustrated embodiment, at the end projecting from the casing, a worm 4 in mesh with a worm gear 5 mounted on a vertical shaft 6, which receives its bearing in a boss 7 on the top wall of the casing 1. The counter-shaft 6, which extends beyond the top surface of the casing, supports in fixed relation thereto a bevel gear 8 in mesh with a bevel gear 9 at the end of a spindle 10, which is disposed horizontally above the top of the 75 casing 1.

This spindle is supported in lugs 11 and 12 above the top surface of the casing near the side walls of the same, and the spindle which has at one end the fixed bevel gear 9 carries at the other end, projecting from the lug 11, a feed roller 13, which is also suitably fixed to the spindle. This roller has a plurality of grooves 14 on its circumference to provide a knurled surface, facilitating the feeding operation of the lace which travels over this roller. A companion roller 15 is grooved at 16, and carries in these annular grooves friction increasing elements 17, in the form of rubber or leather rings, 105 or the like, which, in their operative position, are in engagement with the surface of the first described roller 13. The roller 13 also has a circumferential groove 19, which is disposed midway between, and in opposi- 110

tion to, the rubber or leather rings 17. By the cooperation of these feeding rollers 13 and 15, and also owing to the provision of the friction elements thereon, lace may be 5 uniformly advanced into the machine.

For the purpose of maintaining the companion roller 15 in operative position the shaft 20, supporting this companion roller, is journaled in a sleeve 21, from which the 10 arm 22 extends. The arm 22, integral with the journal sleeve 21 affixed thereto, forms one part of a bell crank lever which is mounted on the pivot 23, supported at one end in the lug 11, and also suitably supported at the other end on the casing. The 15 second arm of the bell crank lever 24 terminates in a cup-shaped sleeve 25, which opens downwardly, and which is telescoped over a cylindrical casing 26, containing a spring 27, which presses the cylinder 26 down into engagement with the top surface of the casing 1, and which at the same time yieldingly forces the sleeve 25 upward. The upper end of the spring 27 acts upon a nut or washer 28, surrounding the reduced end of a set-screw 29, which is threaded through the closed top portion of the sleeve 25, and which also carries a counter-nut 30 to make an adjustment of the spring tension possible 30 through suitable rotation of the set-screw 29 and to lock the parts in adjusted position. It is obvious that the upper roller 15 may readily be lifted from engagement with the lower or companion roller 13 against the 35 tension of the spring 27 within the housing 26; the lever arm 22, on which the roller is mounted, is of advantage for this purpose. A guiding pin 31 is disposed closely to the lower roller 13, and projects from the lug 40 11 outwardly into opposition with said roller.

The space in the axial plane of the two rollers 13 and 15, confined by the annular friction elements 17, and particularly the 45 groove 18, serves for the introduction and support of a threading needle which, as shown in Figs. 1, 2, and 5, consists of a flat steel bar 32, tapered towards one end, and provided at the reduced end with an arrow 50 pointed head 33. This head is pivotally supported by means of a pin 34 between the two prongs 35, in which the needle 32 terminates. The pivotal support of this arrow head is a loose one, so that this arrow may 55 be deflected by the strands of lace which is advanced by the feeding rollers through the machine. The broadened rear end of the needle 32 has an eye 36, through which the end of a ribbon to be threaded into the lace 60 may be introduced. Between the two ends the needle is equipped with openings 37 and 38, which serve for the passage of locking and pivot pins to prevent withdrawal of the needle.

65 An upstanding flange 39 is secured to the

casing in some suitable way, and is provided with brackets 40 and 41, which carry at the outer ends sleeves 42, to receive spring-controlled plungers 43, extending through these sleeves, and provided at their projecting ends with needle points or pins 44. The springs 45 in the cylinders 42 are supported on the bottom of the cylinders and act upon the heads 46 of the plungers 43, to project these plungers normally upward. 70 75

The casing 39 also is provided, in opposition to the cylinders 42, with similar cylinders 47, which receive gravity-controlled plungers 48. These gravity-controlled plungers are each provided with a central bore 80 49, adapted to permit the entry of the pin 44 of the pertaining spring-controlled plunger 43 of the respective upper cylinder.

The device includes mechanism for alternately and selectively actuating the plungers 85 43, the needle points of which serve as locking and pivoting elements of the threading needle 32, and these actuating means also serve for operating simultaneously the gravity-controlled plungers 48, in which the 90 needle is supported, to bring these supports into opposition with the needle points 44, or to permit their withdrawal from engagement with the needle 32. For this purpose a lug 50 extending from the flange 39 upward serves as a support for a rock shaft 51, on which a hand lever 52 is mounted. This hand-lever is provided with projecting arms 53, terminating in enlargements which overlie the heads 46 of the plungers 43. It is 95 obvious, therefore, that upon rocking of the hand lever 52 to one or the other side from a middle position, the ends of the arms 53 will depress either one of the plungers 43, overcoming thereby the action of the springs 100 45, and that the plunger which is not depressed by the arm 53 will be raised by the spring, thereby withdrawing the pin 44 from the needle 32. The lever 52 has a fourth arm 54, which projects downward, and which is equipped with a lateral pin 55, entering a slot 56 of another lever 57, which is pivoted at 58, near the bottom of the casing. This lever has also lateral arms 59, terminating in enlargements which are below, but 105 in permanent contact with, the gravity-controlled plungers 48 of the cylinders 47. From this construction it is apparent that a movement of the hand lever 52 to the right will throw the lever 57 to the left, and, while the right hand plunger 43 may be lowered through this movement of the hand lever 52, the corresponding movement of the lever 57 to the left will cause the gravity-controlled plunger 48 at the right hand side 110 115 to be raised into engagement with the needle 32, whereby the needle point 44 of the plunger 43 will be forced into the central bore 49 of the right hand plunger. 120 125

At the same time the gravity-controlled 130

plunger 48 at the left will drop, remaining, however, in engagement with the end of the corresponding arm 59, and the upper plunger 43 will be raised by the spring, this 5 upward movement being limited by the end of the arm 53, with which the plunger remains in engagement. This toggle lever construction embracing the elements 52 and 57 is held in either one of the selected end 10 positions by means of a spring 60 which, at its upper end, is secured to the handle 61 at the top of the lever 52, while the lower end of the spring may be connected to a pin (not shown) in axial alignment with the pivot 15 pin 58 of the lever 57. This spring 60, therefore, has a tendency to retain the toggle construction in either one of its end positions, and to introduce, by snap action, the toggle structure to this position. Owing to 20 the provision of this spring, the tendency of the lever 52 to remain in a central position will be counteracted and any lack of stability in the structure will thereby be overcome.

25 The operation of the device is about as follows:

The lace, which may be fastened to a garment, or which may be used and threaded with the ribbon independent of its attachment to the garment, is introduced 30 between the rollers 13 and 15 by lifting the upper roller, overcoming the action of the spring 27 in the housing 25. If, then, either by hand or by the motor the motive power 35 for the machine is thrown in, rotation will be imparted to the feeding rollers 13 and 15, and owing to the provision of the frictional projections and indentations on the surfaces of these rollers, the lace will be uniformly and gradually advanced through the 40 space between these rollers. Assuming that a strand of the lace, before starting the motive power, occupies the position indicated in Fig. 7 at S, it is obvious that this 45 strand has a tendency to depress the rear end of the arrow head 33, and to lift the point of the same above the next strand T of the same mesh. If the lace is then advanced along the threading needle 32, the 50 strand S will reach the position indicated in Fig. 8, while the strand T will enter into engagement with the lower edge of the arrow head 33, as shown in Fig. 8. In the advance of the lace this engagement of the 55 strand T with the rear portion of the arrow head will cause a swinging movement of the arrow head 33 to the position indicated in Fig. 9, and this thread then gradually advances on the lower surface of the threading 60 needle, while the thread S proceeds in engagement with the upper surface of the same. The next thread, V, of the mesh will then again engage the upper edge of the arrow head, as shown in Fig. 10, and in its 65 advance will force the rear portion of the

upper arrow head down into that position which is illustrated in Fig. 7. From this it is obvious that in the advance movement of the lace on the threading needle alternate strands, or approximately alternate strands 70 of the lace, will be located on the top and the bottom surface respectively of the threading needle, so that the needle at that time occupies that position which the ribbon finally is to occupy.

75 During this operation the left hand plunger 43, Fig. 2, is lowered to cause its needle point 44 to enter through the opening 38 of the needle, and to hold the same against longitudinal displacement. In the continued 80 advance of the lace, that end of the fabric which has first been placed into the machine will strike against the pin 44, and the advance movement of the lace will thereby be stopped. The result of this operation is that 85 a relatively large length of lace may be gathered on a relatively short length of the needle 32.

When the operator notices that a sufficient 90 length of lace has been gathered or ruffled on the threading needle, she swings the hand lever 52 into the opposite position, and this swinging movement is facilitated by the snap action due to the provision of the spring 60. This movement releases the left 95 hand plunger 43 to the action of the spring 45, which will force the plunger upwardly into the position shown in Fig. 2, and at the same time the other needle point 44 is forced by the arm 53 through the opening 37 in the 100 needle which overlies the central bore 49 of the right hand plunger 48. The spring 60 will also have a tendency to firmly but yieldingly retain the parts in this position. If, 105 then, the motive power should continue to operate, the lace will be gathered on the threading needle 32 in front of the right hand plunger 44, and in the space between the needle 44 and the point at which the 110 rollers 13 and 15 approach each other. It is 115 obviously also possible to shut off the motive power as soon as the right hand plunger 43 has been lowered. The operator may then pull the gathered length of lace rearwardly of the needle, and she may for this 120 purpose turn the needle from straight position into the position indicated in dotted lines in Fig. 5, to facilitate this removal of the lace. In this removal of the lace from the rearward end of the threading needle, the rearward end also supporting the ribbon, which passes preferably from the lower face of the needle through the eye 36 to the upper face of the same. The ribbon is automatically threaded into the lace for that length 125 for which this lace is pulled off the threading needle. The operator then swings the needle again into the interspace between the rollers and throws the lever 52 to left hand position, to lock the needle against longi- 130

tudinal displacement by the rear pin 44. The operation is then again repeated, until the entire piece of lace is uniformly provided with a ribbon threaded through its 5 meshes.

I claim:

1. In a machine of the character described, the combination of a ribbon support, and means for selectively holding said support 10 pivotally on either one of two supporting portions, with which said support is provided.
2. In a machine of the character described, the combination of a ribbon support, and a 15 plurality of co-operating means acting from opposite sides upon said ribbon support for selectively holding the same pivotally at each one of a plurality of points.
3. In a machine of the character described, 20 the combination of a threading needle supporting a ribbon, lace feeding means, the threading needle being provided with a plurality of openings, and means entering said openings for pivotally supporting the needle.
4. In a machine of the character described, 25 a threading needle, means projecting through the needle for determining the point to which lace may be advanced on the threading needle, and lace feeding means, the first 30 named means being adapted to act as a pivotal support for the threading needle.
5. In a machine of the character described, 35 the combination of a threading needle, co-operating feeding rollers for the lace, means for threading the lace on the needle, and means for pivotally supporting the needle, said threading means projecting through the interspace between the feeding rollers.
6. In a machine of the character described, 40 the combination of a threading needle, provided with spaced openings, means for threading lace on the needle, pointed plungers disposed above the openings of the needle, supports for the needle below said 45 openings, and means for selectively actuating the plungers to enter said openings for pivotally supporting the needle.
7. In a machine of the character described, 50 the combination of a threading needle, provided with spaced openings, pointed plungers in opposition to said openings on one side thereof, companion plungers on the opposite side of said needle and in alignment

with said first named plungers, respectively, and means common with each set of companion plungers for actuating the same. 55

8. In a machine of the character described, the combination of a threading needle provided with spaced openings, pointed plungers adapted to enter said openings to form 60 pivotal supports for said needle, means for normally maintaining said plungers in inoperative position, and means for selectively bringing said plungers to operative position.

9. In a machine of the character described, 65 the combination of a threading needle provided with spaced openings, a pair of pointed plungers adapted to said openings, means for normally maintaining said plungers in 70 inoperative position, and selectively operable means for bringing any one of said plungers to operative position, and for permitting said first named means to act upon said 75 plungers to move them, and retain them in inoperative position.

10. In a machine of the character described, 80 the combination of a threading needle provided with spaced openings, a pair of spring controlled plungers above said needle, a pair of gravity influenced plungers below said needle, and selectively operable means for moving oppositely located plungers simultaneously in opposite directions 85 with respect to the needle.

11. In a machine of the character described, 85 the combination of a threading needle provided with spaced openings, a pair of plungers above said needle and centrally disposed with respect to said openings, and actuating means for said plungers, said actuating means including a toggle lever structure connected with the upper and lower plungers whereby, upon actuation of said structure, one set of plungers, including a plunger on each side of the threading needle, 90 is moved to operative position, while simultaneously another set of plungers including also a plunger on each side of the threading needle is moved away from the threading needle. 95

In testimony whereof I affix my signature in the presence of two witnesses.

HANS LUNDQUIST.
